UNITED STATES PATENT OFFICE.

JOSEPH E. WATTS, OF LAWRENCE, MASSACHUSETTS.

DAMPER-REGULATOR.

SPECIFICATION forming part of Letters Patent No. 462,961, dated November 10, 1891.

Application filed April 6, 1891. Serial No. 387,803. (No model.)

To all whom it may concern:

Be it known that I, JOSEPH E. WATTS, a citizen of the United States, residing at Lawrence, in the county of Essex and State of Massachusetts, have invented certain new and useful Improvements in Damper-Regulators; and I do hereby declare the following to be a full, clear, and exact description of the invention, such as will enable others skilled in the art to which it appertains to make and use the same, reference being had to the accompanying drawings, and to figures of reference marked thereon, which form a part of this specification.

15 This invention relates to improvements in damper-regulators in which a thermostat is employed to automatically controlsaid damper and acts dependently upon the amount of heat desired.

20 My invention is embodied in the peculiar arrangement of the several parts by which the regulator can be adjusted to varying degrees of temperature within certain limits, as may be desired or as circumstances dictate.

25 The drawings represent in Figure 1 a side elevation, and in Fig. 2 a front elevation, of a boiler supplied with a regulator containing my invention. Fig. 3 is a plan. In Fig. 1 the fulerum bar or rod is shown in section.

30 In the accompanying drawings is shown a boiler at 2 adapted, preferably, for hot-water circulation and system, and is composed of the usual principal parts—an exterior shell 3, a flue 4, a feed-door 5, and an ash-door or 35 damper 6. The latter is controlled by a damper-regulator, which is composed of a metallic tube 7, preferably one having a large coefficient of expansion. This tube is connected at top and bottom with the boiler to permit free 40 circulation of water or steam therethrough, and by the change in the temperature of such water or steam the position of the damper or ash-door is regulated and the quantity of air admitted to the fire is controlled. The lower

45 part of this circulating tube or pipe 7 is closely fastened to the boiler-shell, thereby rendering this point a fixed one, comparatively speaking. On the other hand, the upper portion is connected by a separate section or elbow-piece 8 in order to allow for the expansion which is to occur at this end, which is intended to be a free end. Secured to each

end of this tube 7 are plates or brackets 9, in which is supported the "contact-post" 10, so termed. This latter is to be made, preferably, of wood with the grain lengthwise, and in which the coefficient of expansion is a minimum. The ends of this post are capped with metal, the lower cap 12 being exteriorly screw-threaded and adapted to engage in the lower 60 plate 9, while the upper one 13 is furnished with a pin 14, moving freely through a hole in the upper plate 9, said pin terminating in a knife-edge. Externally about this post is slipped a loose sleeve 20, which is simply to 65 strengthen the post 10 and prevents it from buckling, but otherwise has no effect upon the action of the said post.

Surmounting the tube 7 and affixed thereto is a support or standard 15, in which a lever 70 16 is pivoted, said lever carrying a counter-balance-weight 17 at one end and being at the other end connected by a chain or other continuous band 18 with the damper 6. This weight is adjustable upon the lever and is to 75 be changed in position according to the weight of the damper and renders the latter perfectly balanced. In this way no work is placed upon the thermostat, but the latter is free to operate according as the temperature varies 80 in the circulating-tube 7.

Before describing the operation of the above mechanism it is to be understood that when the boiler is not in use the damper is open, while the lever is in such position that it rests 85 upon the knife-edge at the extremity of the fulcrum-post 10. This adjustment may be effected by regulating the length of the connecting-chain 18, or, preferably, by axial rotation of the contact-post, which can be raised or 90 lowered in position by turning the lower cap 12, which is split or grooved to admit a screw-driver or other suitable tool for adjustment.

The operation of the several parts is as follows, it being understood that the damper 95 is open, while the lower ends of both the circulating-tube 7 and the fulcrum-post are fixed points. Assuming that the boiler has been fired, as the heat of the water or steam passing through the tube 7 begins to expand it 100 longitudinally the upper free end rises and the lever 16 is lifted on the side carrying the weight. As a consequence the damper is caused to swing and partially close. As wood

with the fibers lengthwise has little or no coefficient of expansion, the length of the contact-post remains of a fixed length, while the expansion and contraction of the tube 7 serve to rock the lever 16, which operates to close the damper as expansion ensues and opens when contraction takes place. The ends of this post 10 are capped in order to have the least amount of metal possible in the construction of said post. In lieu of wood a metallic post may be employed, the only condition, however, being that its coefficient of expansion shall be less than that of the tube 7.

What I claim is—

1. The combination, with the boiler, of a circulating-tube free to expand at one end, a lever supported by said tube, a contact-post having a lesser coefficient of expansion than the said tube and arranged to engage said lever near the fulcrum of the latter, a damper, and a connection between said lever and said damper.

2. The combination, with the boiler, of the circulating-tube 7, connected with said boiler and free to expand at one end, the plates 9, attached to said tube, a contact-post having a lesser coefficient of expansion than the said tube and attached at one end to one of said plates and passing freely through the other of said plates to engage the said lever, a damper, and a connection between said damper and said lever.

3. The combination, with the boiler, of the

circulating-tube 7, the plates 9, attached to said tube, a contact-post 10, having a lesser coefficient of expansion than said tube and arranged to engage the said lever near its fulcrum, said post being adjustably secured at its lower end to one of said plates and passing freely at its upper end through the other of said plates, a damper, and a connection between said damper and said lever.

4. The combination, with the boiler, of the circulating-tube 7, attached to said boiler at one end and free to expand at the other, a lever supported by said tube, a contact-post having a lesser coefficient of expansion than the said tube and arranged to engage said lever near its fulcrum, a damper, a connection between said damper and said lever, and an adjustable weight on said lever to counterbalance said damper.

5. In a damper-regulating mechanism, a wooden contact-post arranged to engage the damper-operating lever and provided with a metallic sleeve loosely but rather closely surrounding said post and serving to stiffen the latter and prevent it from bending or buckling when subjected to strain.

In testimony whereof I affix my signature in presence of two witnesses.

JOSEPH E. WATTS.
